UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

TRANSPORTATION SYSTEM.

1,186,465.

Specification of Letters Patent.

Patented June 6, 1916.

Application filed October 27, 1915. Serial No. 58,252.

To all whom it may concern:

Be it known that I, ADELMER M. BATES, a citizen of the United States, residing at Chicago, in the county of Cook and State of Illinois, have invented a certain new and useful Improvement in Transportation Systems, of which the following is a specification.

My invention relates to a transportation system wherein an overhead traveling pull is first operatively combined with a series of pivotally supported trucks by means of connecting hangers, and it consists among other things in certain improvements in the connecting hanger or some of its parts intended to facilitate the operation and action of the conveyer.

It is illustrated in the accompanying drawings, wherein—

20 Figure 1 is a diagrammatic typical plan view. Fig. 2 is a cross section on the line 2—2 of Fig. 1 looking in the direction indicated by the two small arrows. Fig. 3 is a detail cross section. Fig. 4 is a detail plan, 25 and Figs. 5 and 6 a detail diagrammatic view illustrating the action and operation of the device.

Like parts are indicated by the same letters in all the figures.

30 A, A are the walls of an inclosure, B the floor.

C, C, are a series of hoppers associated with bag filling mechanism D not described or shown in detail.

35 E, E are supporting and projecting beams associated with the bag filling mechanism and furnishing a proper support for a series of brackets F. Similar brackets F are elsewhere supported by projections G, G, suitably mounted on the wall or adjacent thereto as may be desired.

40 All the parts so far described are merely incidental to the invention, and they may be formed and shaped in any desired manner, or of course the bag filling devices could be dispensed with. The drawings, while more or less diagrammatic, are taken from an actual working plant wherein the invention is applied to a conveyer for filled bags associated with mechanisms for filling such bags with cement.

45 J, J are railroad cars, and K, K openings in the building wall opposite the car doors, so as to furnish opportunity for the use of the bridges L, L, which connect the interior of the building with the cars. As pre-

viously suggested, the illustration is taken from a cement plant, and the arrangement is such that the sacks to be filled with cement on one side of the room, are then carried by the conveyer to the other side and there they are wheeled and dumped into the cars.

50 M is a track supported on the bracket F so as to furnish a continuous runway for the hangers. Each hanger consists of a bracket N with a wheel O supported therein, and adapted to run on the track.

55 P is a chain or rope provided at intervals with a series of spools Q, and these spools are adapted to fit into notches R in the sprocket wheel S on the shaft T. There is one of these wheels at each corner, and there might be more if desired, and the system can be set in motion by driving any one or more 60 of said wheels, or any other manner desired. We will assume that it is to be driven in the direction indicated by the arrows in Figs. 1, 5 and 6. The bracket N is secured in any desired manner to one of said spools, 65 and to such spool is secured a connector U, and two adjacent connectors are connected together by the ring V, and to the lower extension W. The connectors U are commonly both of them of flexible material, but 70 one, the rear one having reference to the line of travel, may be of rigid material as indicated at U¹. The extension is preferably provided at its lower end with a relatively 75 rigid section W¹, and an eye W² to engage 80 the hook W³ on the lower middle rearward part of the truck X, which is pivotally supported on the wheels Y. Intermediate the 85 two connectors U and U¹ is a supplementary connector U² of spring material connected 90 at the top to a spool Q intermediate the spools to which the connectors are attached, and at the other end to the ring V, and the 95 spring is adjusted so that when the weight is removed from the extension W, the two 100 connectors U, U¹ are lifted fixed or thrown out of position as indicated in Figs. 5 and 6. Of course it will be understood that 105 these various parts are not here intended to be illustrated as in a final or fixed form. The drawings are to be taken diagrammatically, and illustrative merely of the principle of operation, and no doubt great 110 changes could be made in the particular parts and the details and the form and structure of the several parts without departing from the spirit of invention.

The use and operation of my invention are as follows: In a transportation system of this class various difficulties and objections are encountered, and various advantages are required. It is desirable to shorten the distance between the rear end of the truck and the effective point of connection between the overhead pull and the hanger extension W . It is however at the same time practically necessary to have the pull proper or the endless rope well elevated. This is in part to prevent any irregular motion of the truck. Inequalities of the floor and other inequalities incident to the operation of any such device tend more or less to give the trucks a lunging action in the line of travel, an oscillating action laterally, and if they be well elevated at the rear end, a pivotal action about the supporting wheels. The trucks, however, should be supported as nearly as possible at the point of the balance so that the weight on the handles and the movement of the handles will be very slight when the operator engages the truck with the hanger extension, and when he disengages it. The object is to put the least possible work on the operator and give him the greatest possible freedom in disengaging and engaging the trucks. Inasmuch as the hangers are in motion, and the truck which is to be attached is at rest, it becomes practically necessary to engage the hanger and the truck before the hanger has passed the rear end of the truck, or in other words, the hanger must be swung in the line of travel forward, attached to the truck, and must then be held in engagement until it shall have passed the end of the truck and proceeded far enough on its travel to bring the truck into proper traveling position. When the truck is disengaged, that is, when the filled truck is disengaged, in actual practice the operator will desire at the same moment to engage the previously taken but now empty truck, and this involves the approximately simultaneous use of both hands. One truck is slightly elevated and disengaged from a given hanger extension, and then the empty truck standing near by is brought into engagement with such extension whereupon the operator wheels the filled truck out of the line of travel, and the empty truck is drawn into the line of travel and proceeds on its path. The reverse of this operation is effected at the point where the filled trucks are attached. To carry out these several operations and produce the desired result, I have introduced a spring element in the hanger, which is in this case illustrated by the device U^2 , and this spring element acts as a take-up to flex or loosen the connection sufficiently so that the operator can, by extending the spring element so much as may be required, connect the extension and the truck, and immediately release the same, the spring action

being sufficient to hold the truck in proper relation without disengaging the truck and connector until the truck shall have got into the line of travel, whereupon the spring will be extended and the load will be carried not by the spring but by the connectors U , U . The two positions are somewhat clearly illustrated in Fig. 5. This gives a flexible connector effect to facilitate the engagement and disengagement of the trucks. The rigid portion of any desired length at the end of the extension, or the rigid extension enables the manipulation to be easily made by the operator. The two part connector which is formed by the two connectors U , U , or U^1 , U^1 bring the effective point of engagement between the truck and the pull low down or far below the plane of the traveling rope or chain. The rigid connector still further fixes this point of connection, and minimizes the danger of irregular action.

The idea of arrangement is such that the operator on one side having filled his trucks with bags at one side of the line of travel, will seize one of the hangers and swing it laterally, —it being understood that the connectors which form the two part connectors, are arranged in the same line of travel, and more or less extend the spring and hook the ring into the hook on the filled truck, and by reverse action will seize the empty truck, wheel it out of the line of travel and fill it. In actual practice there will be a series of persons doing this work along one line of the travel, and a corresponding series of persons transferring the filled bags by means of the trucks into the cars at another portion of the line of travel, and there will always be a mixture of filled and unfilled trucks along the two working lines, though elsewhere there will be a line of filled trucks on the one hand, and of empty trucks on the other.

I claim:

1. A transportation system comprising an overhead pull, a lower supporting surface, a truck pivotally supported on said surface at one end, and a detachable yielding connector from the unsupported end of the truck to the overhead pull.

2. A transportation system comprising an overhead pull, a lower supporting surface, a truck pivotally supported on said surface at one end, and a detachable yielding connector from the supported end of the truck to the overhead pull, comprising means whereby the effective line of pull is intermediate the overhead pull and the truck.

3. A transportation system comprising an overhead pull, a lower supporting surface, a truck pivotally supported on said surface at one end, and a detachable connector from the supported end of the truck to the overhead pull, comprising means

whereby the effective line of pull is intermediate the overhead pull and the truck.

4. A transportation system comprising an overhead pull, a lower supporting surface, a truck pivotally supported on said surface at one end, and a detachable connector from the unsupported end of the truck to the overhead pull, said connector having two separate points of engagement with the pull.

5. A transportation system comprising an overhead pull, a lower supporting surface, a truck pivotally supported on said surface at one end, and a detachable connector from the unsupported end of the truck to the overhead pull, said connector having two separate points of engagement with the pull and one point of engagement with the truck.

6. A transportation system comprising an overhead pull, a lower supporting surface, a truck pivotally supported on said surface at one end, and a detachable yielding connector from the unsupported end of the truck to the overhead pull, said connector having two separate points of engagement with the pull.

7. A transportation system comprising an overhead pull, a lower supporting surface, a truck pivotally supported on said surface at one end, and a detachable yielding connector from the unsupported end of the truck to the overhead pull, said connector having two separate points of engagement with the pull and one point of engagement with the truck.

8. A transportation system comprising an overhead pull, a lower supporting surface, a truck pivotally supported on said surface at one end and a detachable connector from the unsupported end of the truck to the overhead pull, comprising two connectors joined intermediate the truck and the overhead pull and connected at separated points to the overhead pull.

9. A transportation system comprising an overhead pull, a lower supporting surface, a truck pivotally supported on said surface at one end and a detachable connector from the unsupported end of the truck to the overhead pull, comprising two connectors joined intermediate the truck and the overhead pull and connected at separated points to the overhead pull, one of said connectors being rigid.

10. A transportation system comprising an overhead pull, a lower supporting surface, a truck pivotally supported on said surface at one end and a detachable connector from the unsupported end of the truck to the overhead pull, comprising two connectors joined intermediate the truck and the overhead pull and connected at separated points to the overhead pull, and a yielding portion connected to the lower

ends of the connectors and to the pull intermediate their upper ends.

11. A transportation system comprising an overhead pull, a lower supporting surface, a truck pivotally supported on said surface at one end and a detachable connector from the unsupported end of the truck to the overhead pull, comprising two connectors joined intermediate the truck and the overhead pull and connected at separated points to the overhead pull, one of said connectors being rigid, and a yielding portion connected to the lower ends of the connectors and to the pull intermediate their upper ends.

12. A transportation system comprising an overhead pull, a lower supporting surface, a truck pivotally supported on said surface at one end and a detachable yielding connector from the unsupported end of the truck to the overhead pull, comprising two connectors joined intermediate the truck and the overhead pull and connected at separated points to the overhead pull.

13. A transportation system comprising an overhead pull, a lower supporting surface, a truck pivotally supported on said surface at one end and a detachable yielding connector from the unsupported end of the truck to the overhead pull, comprising two connectors joined intermediate the truck and the overhead pull and connected at separated points to the overhead pull, one of said connectors being rigid.

14. A transportation system comprising an overhead pull, a lower supporting surface, a truck pivotally supported on said surface at one end, and a detachable yielding connector from the unsupported end of the truck to the overhead pull, said connector provided with a rigid portion near the point of its engagement with the truck.

15. A transportation system comprising an overhead pull, a lower supporting surface, a truck pivotally supported on said surface at one end, and a detachable yielding connector from the supported end of the truck to the overhead pull, comprising means whereby the effective line of pull is intermediate the overhead pull and the truck, said connector provided with a rigid portion near the point of its engagement with the truck.

16. A transportation system comprising an overhead pull, a lower supporting surface, a truck pivotally supported on said surface at one end, and a detachable connector from the supported end of the truck to the overhead pull, comprising means whereby the effective line of pull is intermediate the overhead pull and the truck, said connector provided with a rigid portion near the point of its engagement with the truck.

17. A transportation system comprising

- an overhead pull, a lower supporting surface, a truck pivotally supported on said surface at one end, and a detachable connector from the unsupported end of the truck to the overhead pull, said connector having two separate points of engagement with the pull, and provided with a rigid portion near the point of its engagement with the truck.
- 10 18. A transportation system comprising an overhead pull, a lower supporting surface, a truck pivotally supported on said surface at one end, and a detachable connector from the unsupported end of the truck to the overhead pull, said connector having two separate points of engagement with the pull and one point of engagement with the truck, said connector provided with a rigid portion near the point of its engagement with the truck.
- 15 19. A transportation system comprising an overhead pull, a lower supporting surface, a truck pivotally supported on said surface at one end, and a detachable yielding connector from the unsupported end of the truck to the overhead pull, said connector having two separate points of engagement with the pull, and provided with a rigid portion near the point of its engagement with the truck.
- 20 20. A transportation system comprising an overhead pull, a lower supporting surface, a truck pivotally supported on said surface at one end, and a detachable yielding connector from the unsupported end of the truck to the overhead pull, said connector having two separate points of engagement with the pull and one point of engagement with the truck, said connector provided with a rigid portion near the point of its engagement with the truck.
- 25 21. A transportation system comprising an overhead pull, a lower supporting surface, a truck pivotally supported on said surface at one end and a detachable connector from the unsupported end of the truck to the overhead pull, comprising two connectors joined intermediate the truck and the overhead pull and connected at separated points to the overhead pull, said connector provided with a rigid portion near the point of its engagement with the truck.
- 30 22. A transportation system comprising an overhead pull, a lower supporting surface, a truck pivotally supported on said surface at one end and a detachable connector from the unsupported end of the truck to the overhead pull, comprising two connectors joined intermediate the truck and the overhead pull and connected at separated points to the overhead pull, one of said connectors being rigid and provided with a rigid portion near the point of its engagement with the truck.
- 35 23. A transportation system comprising an overhead pull, a lower supporting surface, a truck pivotally supported on said surface at one end and a detachable connector from the unsupported end of the truck to the overhead pull, comprising two connectors joined intermediate the truck and the overhead pull and connected at separated points to the overhead pull, and a yielding portion connected to the lower ends of the connectors and to the pull intermediate their upper ends, said connector provided with a rigid portion near the point of its engagement with the truck.
- 40 24. A transportation system comprising an overhead pull, a lower supporting surface, a truck pivotally supported on said surface at one end and a detachable connector from the unsupported end of the truck to the overhead pull, comprising two connectors joined intermediate the truck and the overhead pull and connected at separated points to the overhead pull, one of said connectors being rigid, and a yielding portion connected to the lower ends of the connectors and to the pull intermediate their upper ends, said connector provided with a rigid portion near the point of its engagement with the truck.
- 45 25. A transportation system comprising an overhead pull, a lower supporting surface, a truck pivotally supported on said surface at one end and a detachable yielding connector from the unsupported end of the truck to the overhead pull, comprising two connectors joined intermediate the truck and the overhead pull and connected at separated points to the overhead pull, said connector provided with a rigid portion near the point of its engagement with the truck.
- 50 26. A transportation system comprising an overhead pull, a lower supporting surface, a truck pivotally supported on said surface at one end and a detachable yielding connector from the unsupported end of the truck to the overhead pull, comprising two connectors joined intermediate the truck and the overhead pull and connected at separated points to the overhead pull, one of said connectors being rigid, said connector provided with a rigid portion near the point of its engagement with the truck.
- 55 In testimony whereof, I affix my signature in the presence of two witnesses this 22d day of October 1915.
